UNITED STATES PATENT OFFICE.

PHILIP SUSMAN, OF NEW YORK, N. Y., ASSIGNOR TO COMMERCIAL HEADWEAR CO., INC., A CORPORATION OF NEW YORK.

DESIGN FOR A HAT.

Application filed June 14, 1924. Serial No. 9,870. Term of patent 3½ years.

To all whom it may concern:

Be it known that I, PHILIP SUSMAN, a citizen of the United States, residing at New York city, county of New York, and State of New York, and doing business at 654 Broadway, New York city, N. Y., have invented a new, original, and ornamental Design for a Hat, of which the following is a specification, reference being had to the accompanying drawings, forming part thereof.

The figure is a perspective view of the hat showing my new design.

I claim:

The ornamental design for a hat, as shown.

PHILIP SUSMAN.
